(57) **CLAIM**

The ornamental design for a welding face shield with side panel, as shown and described.

DESCRIPTION

FIG. 1 is a top perspective view of a welding face shield with side panel showing my new design;

FIG. 2 is a front view thereof;

FIG. 3 is a right side elevational view thereof;

FIG. 4 is a left side elevational view thereof;

FIG. 5 is a back view thereof;

FIG. 6 is a top plan view thereof;

FIG. 7 is a bottom plan view thereof; and,

FIG. 8 is a left side elevational view thereof shown in an environment related to the use of the claimed design.

The broken lines showing a person with a head strap and block for securing the welding face shield are provided for the purpose of illustrating environmental structure related to the claimed design.
